7 Claims. (Cl. 37—187)

1

In all the heretofore existing types of grab-buckets, the fitting thereof to the various types of lifting gear requires special mechanisms which are totally different from one another and which involve extensive modifications in the construction of the bucket, so that such mechanisms cannot be manufactured by mass production.

Furthermore, the closing mechanisms, cables or rods, are exposed to the open air, i. e. are in direct contact either with the goods or with the substances in suspension in the air due to the manipulation of powdery goods. Consequently, there is a fairly large amount of wear of the various parts of the mechanism.

The invention has for its object an actuating mechanism which is adapted on the one hand to be used such as it is or with insignificant modifications which can be readily effected irrespective of the arrangement of the cables and lifting gear, and on the other hand to be enclosed in a fluid-tight casing forming an oil bath, which shields all the actuating members from dust or substances in suspension in the air.

According to the invention, the mechanism comprises a central box-like member to which the two bucket or grappling elements of the bucket are pivotally connected and which supports a rocking toothed quadrant which is adapted to mesh with one or more pinions connected to the member for actuating the bucket elements and is connected to the pivots of said bucket elements by means of a system of connecting rods which is coupled to two pins fixed at two eccentric points on the quadrant.

According to another feature, the central box-like member is formed by two identical fluid-tight casings which contain two identical bucket-element actuating mechanisms and which are located symmetrically with respect to the longitudinal medial plane of the bucket and are braced by two tubular sleeves containing the pivots of the bucket elements, the ends of the shafts of the closing drum and of the pivots of the systems of opening levers being journalled in bearings supported by said casings.

The device thus constructed can be mounted on all types of grab-buckets and its arrangement furthermore enables the lifting and opening cables, whatever the number and the position thereof, to be connected to the bucket in such a manner that they are always located substantially in the axis of the bucket, thereby avoiding the use of deflecting members and decreasing their wear.

Other features will become apparent from the ensuing description.

2

In the accompanying drawings which are given solely by way of example:

Fig. 1 is a diagrammatic vertical section of one embodiment of the device according to the invention in the closed position;

Fig. 2 is an end elevation corresponding to Fig. 1, partly in section along the line 2—2 of Fig. 1;

Fig. 3 is a half plan view corresponding to Fig. 1, partly in section along the line 3—3 of Fig. 1;

Fig. 4 is a similar view to Fig. 1 in the open position;

Fig. 5 is a side elevation of an auxiliary device;

Fig. 6 is a front elevation corresponding to Fig. 5;

Figs. 7 and 8 are diagrammatic plan views of two methods of mounting the device of Fig. 1;

Fig. 9 is a similar view of Fig. 1 on a smaller scale, of another embodiment of the device;

Fig. 10 is a plan view corresponding to Fig. 9;

Fig. 11 is a fragmentary vertical section of another embodiment in the closed position;

Fig. 11a is a fragmentary view corresponding to Fig. 11 at an enlarged scale;

Fig. 11b is a fragmentary view corresponding to Fig. 11 in another position of the device;

Fig. 12 is a fragmentary section of the device of Fig. 11 in the open position;

Fig. 12a is a fragmentary view corresponding to Fig. 12 in another position of the device;

Fig. 13 is an elevational view of a detail of the device of Figs. 11 and 12;

Fig. 14 is a vertical section of another embodiment.

In the foregoing description of the figures, mention has been made of several embodiments of the device according to the invention, but it would be more correct to speak of several methods of adapting, according to the nature and the position of the actuating members (opening and closing cables and drums) of one and the same device which, as will be explained hereinafter, can be originally constructed in such a manner as to enable it to be used without modifying its members in any of the cases considered.

In Figs. 1 to 4, an embodiment is shown that corresponds to an actuating mechanism comprising a central lifting and closing cable and two opening cables arranged on either side transversely with respect to the opening movement of the bucket elements.

1 is the lifting and closing cable, 2 are the opening cables. The central box-like member to which the grappling elements 3 are pivotally connected is formed by two longitudinal casings 4 braced by two tubes 5 forming housings for sta-

tionary shafts 6 on which are journalled, preferably by means of needle-bearings, cylindrical blocks or shafts 7. Each grappling element 3 is fixed at the top of its two side plates to the blocks 7, for example by means of a mortise and tenon 8 with clamping by means of a bolt 9.

At the point where each block 7 passes through it, the wall of the casing 4 is reinforced at 10 and forms a bearing with a fluid-tight joint 11.

The lifting cable 1 winds on a drum 12 supported by a shaft 13, the two ends of which pass through each of the casings 4 so as to be journalled in said casings. On each of the ends of the shaft 13, which is confined in the casing 4, is keyed a pinion 14 that meshes with internal teeth 15 provided on the edge of an arcuate groove 16 formed in a quadrant 17 adapted to rock on a shaft 18 supported by the casing 4. Said pinion 14 is completely housed in the groove 16. At two points of the quadrant 17, which are eccentric and opposite with respect to the shaft 18, are mounted two pins 20 to which are pivotally connected two double connecting rods 21, the other ends of which are pivotally connected to pins 22 supported by cranks 23 secured to the blocks 7.

It will immediately be understood that any rotation of the quadrant 17 about its shaft 18 in either direction, by means of the connecting rods 21, the cranks 23 and the blocks 7, produces a corresponding rotation of the grappling elements 3 about their pivots 6.

The end of each opening cable 2 is fixed to the free end of a lever 24 secured to a sleeve 25 keyed on a shaft 26 which is parallel to the shafts 6 and 13 and which like them, is rotatably mounted in the casings 4. On each of the ends of the shaft 26, which is confined in a casing 4, is keyed a second sleeve 27 secured to a lever 28 which forms a crank with the lever 24 and the free end of which acts, by means of a pin 29, as a pivot for a connecting rod 30, the other end of which is pivotally connected to an eccentric point 31 of the quadrant 17, said point 31 being so located that a rotation in the direction f (Fig. 4) of the lever 24 causes the quadrant 17 to rotate in the opposite direction to that which is imparted to it by the closing cable 1 as it unwinds, i. e. when the drum 12 and the pinion 14 are rotating in the direction f_1 .

The operation of the device is obvious: having placed the bucket in the open position on a heap of materials, as shown in Fig. 4, the cables 2 are slackened and the cable 1 is pulled, the drum 12 rotates in the direction f_1 and the quadrant 17 rocks in the direction f_2 , causing by means of the connecting rods 21, the grappling elements 3 to close together, i. e. the bucket to close, said bucket then being lifted by the cable 1. During this time, the rotation of the quadrant 17 has caused the system of levers 30, 28, 24 to rotate about the pivot 26, the levers 24 being moved downwards in the opposite direction to f and assuming the position of Fig. 1.

In order to obtain the opening of the bucket, it is only necessary, after slackening the cable 1, to pull the cables 2, thereby causing the lever 24 to rotate in the direction f and consequently the quadrant 17 to rock in the opposite direction to f_2 , which causes the bucket elements to open and the drum 12 to rotate in the opposite direction to f and thus wind the necessary length of the cable 1 for the opening movement.

In Figs. 5 and 6 an auxiliary device is shown that enables the actuating mechanisms to be

released during the manipulation of the full bucket. In this position, the whole weight of the bucket is transmitted to the cable 1 by means of said mechanisms (connecting rods 21, quadrant 17, pinion 24 and drum 12) and therefore produces strains on same which are unnecessary as regards the operation and harmful as regards wear. The purpose of the device of Figs. 5 and 6 is to effect the transmission of the weight of the closed bucket directly to the lifting cable 1 by means of the drum 12. For this purpose, on a lateral flange 32 secured to the drum 12 is provided an abutment 33 which is adapted to engage the nose of a pawl 34 which is so mounted as to rock with the shaft 26 either rigidly or preferably semi-rigidly with the interpolation of a spring 35. The position of the abutment 33 is so calculated that it only encounters the pawl 34 which is resting against the flange 32 when the lever 24 is at the bottom of its closing travel so that the bucket is closed. At the instant of opening, the movement of the lever 24 in the direction of f automatically produces the retraction of the pawl 34 thereby releasing the drum 12 and enabling the cable 1 to be wound.

It will be seen that when the pawl 34 is engaged with the abutment 33, the drum 12 is rigidly connected to the shaft 26 and to the casings 4 and the lifting force is therefore directly transmitted to the stationary members of the bucket without passing through the actuating mechanisms.

In the example which has just been described, the constant elements which exist in all the methods of adapting the bucket are:

The casings 4, the tubes 5, the pivots 6, the blocks 7 and the devices for connecting them to the bucket elements 3, the shaft 13, the shaft 26, the pinions 14, the quadrants 17 and the linkage 21, 23 and 28, 30. All these elements form a standard unit, all the moving parts of which are shielded from the dust inside the fluid-tight casings 4.

In Figs. 7 and 8, two different methods of adapting the device of Fig. 1 are shown, in the case of a hoist with two lifting or closing cables and two opening cables located in the same plane at right angles to the direction of opening of the bucket.

In this case the device is provided with two drums 12 which are mounted on the existing shaft 13 in such a manner as to be located, according to the respective position of the cables, at the centre and between the levers 24, or at the sides, the levers 24 being located at the centre.

In Figs. 9 and 10, a method of adapting the device is shown in the case of a hoist comprising two lifting cables in a plane parallel to the direction of opening of the bucket and two opening cables in a plane at right angles thereto.

In this case, a second shaft similar to the shaft 13 is arranged between the casings 4 and carries a second drum 37 located at the centre in alignment with the drum 12. The shaft 36 drives two pinions 38 which are arranged like the pinions 14 in the casings 4 and, for facilitating mounting the quadrant 17 is reversed, the pinion 38 meshing with the internal teeth 15 and the pinion 14 meshing with external teeth provided at 39 on the quadrant 17 opposite the teeth 15. One of the connecting rods 21 is replaced by a bent connecting rod 40 in order not to hinder the mounting.

The operation of the device is identical and both the sets of teeth 15 and 39 co-operate to

close the bucket, the diameters of the drum 12 and 37 being so chosen as to compensate for the difference of ratio between the two sets of teeth.

It should be observed that the connection between the two drums 12 and 37 could be effected in a different manner by using only one set of teeth and for example winding the cables in opposite directions on the drum.

Of course, the actuating mechanism unit may be provided at the outset with a shaft 36, a second set of teeth 39 on the quadrant 7 and a bent connecting rod 40, and these elements would be used or not according to the position and the number of the actuating cables.

The method of adapting according to Figs. 11 to 13 corresponds to the application of the invention to the case of an automatic grab-bucket with opening crown, the opening control of which is effected by means of a ratchet motion according to a well known method.

In this case the bucket is not provided with an opening cable and a stationary crown 41 through which the lifting cable or cables 1 pass is suspended in a fixed position above the bucket. The crown 41 is provided with pawls 42 and with a vertically movable plunger ring 43 adapted to actuate said pawls 42 by means of slots 43a (see Fig. 11a).

On a cross-piece 44 forming an abutment, supported by the casings 4, rests, preferably by means of a spring 45, a slider 46 through which passes the lifting cable 1 and which is provided with a nose 47 adapted to engage the pawl 42 of the crown 41.

To the slider 46 are pivotally connected two rods 48 which are connected at their other end to the two levers 24 located on either side of the drum 12 (see Fig. 13), and a second cross-piece forming an abutment 49, likewise supported by the casings 4, is adapted to come into contact with the movable ring 43 of the crown 41.

Finally, the drum 12 is provided at the side with a ratchet wheel 50 which is adapted to come into engagement with a pawl 51 supported by the shaft 26 and rotated by means of stops 52 secured to the shaft 26, and 53 secured to the pawl 51 and with the interpolation of a spring 54.

The device operates as follows: when the bucket is being lifted in the closed state as represented on Fig. 11, it comes into contact with the opening crown 41, the slider 46 comes into said crown and the support 49 engages the ring 43 in an upward movement which allows the pawls 42 supported by the crown 41 and which are no more in contact with the upper end of the slots 43a, to rotate by gravity, said pawls thus engaging under the nose 47 provided on the slider 46 (see Fig. 11b).

By slackening the lifting cable 1, the bucket moves downwards and the slider 46 resting against the pawls 42 (Fig. 12), the lever 24 rotates and causes the bucket to open and the pawl 51 to rotate towards the ratchet wheel 50. When the opening of the bucket is completed, the pawl 51 rests against the ratchet wheel 50.

If a pull is then exerted on the cable 1, the drum 12 drives the ratchet wheel 50, one of the teeth of which comes into contact with the pawl 51 and prevents the bucket from closing again (Fig. 12). The bucket is then lifted slightly, the nose 47 moves out of contact with the pawls 42, the ring 43 falls downwards by gravity and causes the pawls 42 to rotate towards their retracted position (see Fig. 12a) and to release the slider 75

46 and the bucket which thus may move downwards again open.

When the bucket is resting on the goods and the cable 1 is slackened, the pawl 51 is retracted by the action of the spring 52 and releases the closing drum 12; the bucket can then be closed again.

It can be seen that in this case also all the essential elements of the mechanism remain the same and the new elements can be added without any modification of the device itself.

In Fig. 14 the adaptation of the device to an electrically actuated bucket is shown. In this case the shaft 13 is driven by a worm wheel 55 which replaces the drum 12 and meshes with a worm 56 which is driven through a power limiting device 57 of any type by an electric motor 58 supported by a cross-member 59 fixed to the casing 4.

20 The mechanisms inside the casings 4 are unchanged and only an abutment (not shown) is provided for limiting the rotation of the quadrant 17 in the opening direction of the bucket.

Having now described my invention what I claim as new and desire to secure by Letters Patent is:

1. An operating device for grab mechanism of the type comprising two grappling elements, a hoisting cable for controlling the closing motion of said elements and a drum for said hoisting cable, which comprises a central box-like member to which said elements are pivotally connected, a stationary crown and a movable pawl device supported by said box-like member and adapted to engage said crown, a rocking toothed quadrant carried by said box-like member, a pinion meshing with said toothed quadrant and connected to said drum, a system of rods connected at one end to the pivots of said grappling elements and, at the other end, to two pins fixed at two eccentric points of said quadrant and a system of levers connected at one end to said pawl device and, at the other end, to a pivot fixed at an eccentric point of said quadrant, and pivotally carried by said box-like member.

2. A device according to claim 1 further comprising a toothed wheel secured to said drum and a resilient retracting pawl adapted to engage, in the open position, said toothed wheel.

3. An operating device for grab mechanism of the type comprising two grappling elements, a hoisting cable for controlling the closing motion of said elements, a drum for said hoisting cable and means for controlling the opening motion of said elements, which comprises a central box-like member to which said elements are pivotally connected, a rocking toothed quadrant carried by said box-like member, a pinion meshing with said toothed quadrant and connected to said drum, a system of rods connected at one end to the pivots of said grappling elements and, at the other end, to two pins fixed at two eccentric points of said quadrant, a system of levers connected at one end to said means for controlling the opening motion of the grappling elements and, at the other end, to a pivot fixed at an eccentric point of said quadrant, and pivotally carried by said box-like member, an abutment carried by said drum and a retractable pawl controlled by said system of levers and adapted to engage said abutment in the closed position.

4. An operating device for grab mechanism comprising a central box-like member, two grappling elements pivotally connected to said member, a drum carried by said member, a

hoisting cable for controlling the closing motion of said grappling elements adapted to wind on said drum, a rocking toothed quadrant carried by said member, a pinion connected to said drum and meshing with said quadrant, rods connected at one end to said grappling elements and at the other end to two eccentric points of said quadrant, a system of levers pivotally carried by said member and connected at one end to an eccentric point of said quadrant and means for controlling the opening motion of said grappling elements and adapted to engage the other end of said system of levers.

5. A device as claimed in claim 4 wherein said means for controlling the opening motion of said grappling elements comprises a cable fixed to the corresponding end of said system of levers.

6. An operating device as claimed in claim 4 wherein said box-like member comprises a casing filled with oil and housing said rocking quadrant, 20 pinion, rods and the portion of said system of levers connecting said quadrant to said box-like member.

7. An operating device for grab mechanism comprising two grappling elements, a central box-like member, a drum carried by said member, a hoisting cable for controlling the closing motion of said elements and adapted to wind on said drum, a pair of shafts pivotally mounted on said member and carrying said grappling elements, a 25 third shaft pivotally mounted on said member, actuating levers rigidly mounted on said third shaft, and means for controlling the opening mo-

tion of said grappling elements and adapted to engage the free ends of said levers, said box-like member comprising on each side of said drum two parallel and identical casings filled with oil, connected together by tubular sleeves and each containing a rocking toothed quadrant, a pinion meshing with said quadrant and connected to said drum, rods connected at one end to said pair of shafts carrying said grappling elements and at the other end to two eccentric points of said quadrant, and a system of levers connected at one end to an eccentric point of said quadrant and at the other end to said third shaft.
